UNITED STATES PATENT OFFICE.

JACOB W. LATTIG, OF BETHLEHEM, PENNSYLVANIA, AND CHARLES L. GOODRUM, OF NEW YORK, N. Y., ASSIGNORS TO WESTERN ELECTRIC COMPANY, INCORPORATED, OF NEW YORK, N. Y., A CORPORATION OF NEW YORK.

AUTOMATIC TELEPHONE-EXCHANGE SYSTEM.

Original application filed August 29, 1904, Serial No. 222,657. Divided and application filed October 12, 1917, Serial No 196,125. Divided and this application filed December 24, 1921. Serial No. 524,724.

To all whom it may concern:

Be it known that we, JACOB W. LATTIG and CHARLES L. GOODRUM, citizens of the United States, residing at Bethlehem, in the county of Lehigh and State of Pennsylvania, and at New York, in the county of New York and State of New York, respectively, have invented certain new and useful Improvements in Automatic Telephone-Exchange Systems, of which the following is a full, clear, concise, and exact description.

This invention relates to telephone exchange systems, and is a division of application Serial No. 196,125 filed October 12, 1917, which is a division of application Serial No. 222,657, filed August 29, 1904.

In multi-office telephone systems it is the practice to supply talking current to the subscribers' lines from the offices in which the subscribers' lines terminate and to interconnect the offices by trunks consisting of only two conductors. These trunk conductors are also used to control the setting of the automatic switches at the distant office.

It is the object of this invention to employ these same trunk conductors to operate an electro-responsive device at the originating office at a certain stage in the process of building up a connection to operate metering or supervisory equipment, thus avoiding the necessity of providing additional conductors for this purpose.

In accordance with this invention an electro-responsive device is connected to each outgoing trunk which device is responsive to a change brought about in the trunk circuit at a certain stage in the process of building up the connection, as for example when the called party answers, and which device in operating causes the operation of call charging equipment associated with the calling line.

More specifically, and as applied to a call registering mechanism for automatic telephone systems, a meter control relay is connected to each of the inter-office trunks at the originating office and upon the response of the called party current of the proper character is caused to be applied to the trunk at the distant office, which operates this meter control relay, this latter relay in operating, closing a circuit including a cen-

tral office meter individual to the calling line, which meter thus records the call.

Preferably each inter-office trunk is provided with two polarized relays. The response of the called party, if the called line is not a free or official line, operates a relay in the connector which applies current to the trunk to operate one of said polarized relays. This relay in operating supplies talking current to the calling line in the proper direction to operate the meter, which is connected in the line circuit at the central office.

If the called line is a free line, the relay in the connector which operates upon the response of the called party applies current to the trunk which flows in the proper direction to operate the other of said polarized relays. This relay in operating supplies talking current to the calling line which is not of the proper direction to operate the said meter magnet.

Our invention is illustrated in the accompanying drawings, wherein the same letters of reference apply to the same parts throughout. In these drawings,

Fig. 1 is a diagram of a subscriber's line and substation apparatus, together with the first selector for that line; Fig. 1^a is a diagram of a trunk circuit leading from a first selector to a second selector; Fig. 2 is a diagram of the circuits of a second selector; Fig. 3 is a diagram of the circuits and connections of a connector; and Fig. 4 is a diagram of a subscriber's line, its substation apparatus, and its first selector, the connection to the multiple bank of the connector of Fig. 3 being shown in heavy lines at the left.

We have not illustrated the switch mechanism in detail as regards its mechanical parts, more particularly because our invention is not limited to a specific switch, but may be practiced with any one of a number of automatic switches. As the circuits are shown, however, for the sake of illustration we will refer to the following patents, in which the so-called Strowger type of switch is shown, this being with some modifications hereafter referred to, adapted for use with these circuits. The patents are: 591,201, Oct. 5, 1897, Strowger, Lundquist and Erick-

son; 638,249, Dec. 5, 1899, Keith and Erickson; 672,942, Apr. 30, 1901, Keith and Erickson.

We do not illustrate all of the apparatus at the subscriber's station for the reasons already given. Here also our invention may be practiced with several types of apparatus, although for the sake of illustration here we have shown a part of the well-known Strowger type of apparatus.

Before proceeding to the detailed description, we will state the parts and functions of the apparatus which we here show, the circuits for the same, and the modifications therein caused by the application thereof to our purposes.

In this system all talking circuits are metallic, that is are composed of two line wires; and in addition we employ a ground return. Each line terminates in the central office in a first selector, corresponding to the answering jack of a manual multiple switchboard, and also is connected to multiple contacts in the several banks of connectors, to which reference will presently be made.

Each selector switch is a self-contained unit individual to its line, and each contains a multiple contact for each of the second selectors. Each second selector is also a self-contained unit, connected to its various multiples in the first selectors through a trunk line, and each contains a multiple contact in its banks for each connector.

Each connector is a complete switch unit connected to its multiples in the various second selector banks and each connector contains in its banks contacts for the subscribers' lines falling within its range, usually one hundred lines.

The mode of selection of a wanted subscriber, briefly stated, is as follows: The calling subscriber, through the operation of his impulse sender sets the first selector to connect with an idle second selector in the set containing the thousands terminals corresponding to the thousands digit in the number wanted; this cuts off the first selector magnets, whereupon he sets the second selector switch in a similar manner to put himself in connection with the terminal contact of an idle connector in the hundreds group corresponding to the hundreds digit in the number wanted; this cuts off the second selector magnets, whereupon he sets the connector switch to select a multiple terminal of the particular line wanted. As the connection progresses step by step, the metallic talking circuit is correspondingly extended through the first and second selectors and the connector, unbroken to the latter, but therein separated by condensers. The main battery is bridged across this circuit on the end toward the called subscriber, but until the latter answers there is no

bridged battery on the calling end. All the signaling is done over one or the other line wire and the ground. The connection being completed (that is the line wanted not being found busy) the calling subscriber pushes his button and a ringing relay in the connector circuit impresses ringing current on the wanted line. When the called subscriber answers he automatically operates relays in the connector circuit which cut back the main bridged battery on the calling end of the talking circuit. When the conversation is finished and the subscribers have hung up their receivers, a release magnet in each of the intermediate circuits trips the mechanism and all of the switches are restored to normal.

Fig. 1 shows a pair of line wires 1-2 constituting a subscriber's line circuit and extending from the first selector to several subscriber's stations A, A', and A² and A³. The station A is shown in full, connected to the line wires 1 and 2 by the branches 3 and 4. The stations A', A², A³ are all the same as station A, each being connected across the line by its own pair of branches 5-6, 7-8, or 9-10. The line 1-2 therefore is a party line, and as will appear later the stations are adapted to be signaled selectively. At each subscriber's station a transmitter T, a receiver R, an induction coil I^c, a switch-hook H, a ringer Q and condenser C, are provided. In addition to these any suitable impulse transmitter is mounted on the set. Each operation of the impulse transmitter sends the desired number of impulses over the vertical side of line, and then a single impulse over the rotary side of line. It may be well here to explain the meaning of these terms vertical and rotary. In connection with the Strowger switch they have a specific significance, but in our specification they are used for convenience, and not as a limitation to a Strowger switch. In this switch there is a vertical spindle v (see Fig. 1) carrying wipers or contact springs v' and v² which are adapted to pass over and make connection with bank contacts m' and m². These bank contacts, as shown in the patents hereinbefore referred to, are arranged in horizontal rows of ten. The banks of rows are arranged in semicircular form with the center of their radii in the axis of the vertical spindle v. In order to bring the wipers into contact with any particular contacts m' and m² therefore the spindle v is first stepped up until each wiper is opposite the desired row, and then is turned around step by step until the wipers come in contact with the desired particular terminals in the row. The first movement of the spindle is called the vertical movement, and the second the rotary movement. From these two descriptive terms the words vertical and rotary

have come to be applied to the two line wires, although in the present system, as will appear later, the selecting impulses are all sent over the vertical side of line. These 5 terms will be employed herein for convenience to designate the two line wires, while the various magnets and other parts of the apparatus will be designated as vertical and rotary to distinguish their 10 functions.

Returning to the subscriber's station A, we have said that the transmitter should send selective impulses over the vertical side of the line, and a single impulse at the end 15 of each group over the rotary side. This is accomplished by a sender (not shown) acting in conjunction with certain groups of contact springs a , a' , a^2 , a^3 , a^4 , a^5 , a^6 , a^7 , a^8 , a^9 , a^{10} , a^{11} , a^{12} , a^{13} , a^{14} , and a^{15} , together with the 20 hook lever H. The functions of these several springs will appear more particularly from the statement of operation hereafter.

The receiver R is shown in a local circuit 21 terminating in one winding of the induction coil I, this being in effect the same as cutting off the receiver by a condenser so that battery current will not flow through it and its resistance is removed from the line. The transmitter circuit for the common 25 battery system may be traced as follows: from vertical line wire 11 by branch 3, wire 25, spring a , wire 26, spring a^5 , spring a^6 , wire 24, springs a^{14} and a^{15} , line winding of induction coil I, transmitter T by wire 23, and 30 thence by wire 22, springs a^8 and a^9 and wire 21 to the rotary side of line 12, through the branch 4.

The ringer Q is in a ground tap from branch 4 on the rotary side of line, with an 40 interposed condenser C. The spring a^4 is grounded at G through a resistance r , for a purpose to be presently disclosed.

It is to be understood that no substantial change is required in the subscriber's instrument to convert this system back into a local battery system, the apparatus remaining the same and the only changes being in the receiver and transmitter wiring.

Passing to the central office, the metallic 50 talking circuit wires 11 and 12 pass through the first selector S, and terminate in the switch arms f' and f^2 of what we shall designate as the "side-switch" F. This side-switch comprises four arms moving together 55 over a series of contacts, there being three contacts for each arm. These arms are lettered respectively f , f' , f^2 , and f^3 . Arm f cooperates with contacts f^0 , f^{10} , and f^{20} , being normally in contact with f^0 . Similarly and 60 synchronously the other arms move over their corresponding contacts during the operation of the apparatus, being normally in contact with the point f^0 in each case.

The vertical wire 11 is normally connected 65 through arm f' and wire 30 to the vertical

relay D, thence by wire 31 through the cut-off springs k^3 , k^2 , and k' through wire 32 to the grounded main battery B. The rotary wire 12 is normally connected through arm f^2 by wire 34 to the rotary relay E, 70 thence by wire 33, spring k^2 and k' , and wire 32 to the same battery.

In their normal condition it is apparent that the wires 11—12 are severed from the wipers v' , and in the severed conductors leading from the contacts f^{20} to the wiper contacts v' , we interpolate the two equal and opposite windings of a differential relay O, shown in the diagram as having an armature o normally closed upon a contact o' , connected by wire 35 with the busy-switch U, through the contacts u and u' thereof to the bridge cut-off magnet K, and by wire 32 to the main battery. The armature o is connected on the other side by wire 36 to the 80 private contacts m^{10} , m^{12} , m^{14} , and m^{16} in the several banks allotted to the various parties on the line. We should state that this differential relay is used in connection with party lines only. Its winding and connections are such that under normal conditions of current flow in the metallic circuit the armature remains unaffected, and the alternating currents encounter no substantial retardation, either because of twin winding 85 or of a copper jacket.

The vertical relay D controls through its armature a contact spring d to close the same on a ground contact g . Spring d is connected by wire 37 through the springs p^2 — p' 100 and wire 38 to the vertical magnet D' (which actually does the vertical moving of the spindle v) thence by wire 39 to the main battery wire 32.

The relay E through its armature controls 105 a spring e adapted to close on the same ground contact, spring e being connected by wire 390 to the private magnet P and thence to the main battery wire 32. From the wire 390 branch 40 extends to the second contact 110 f^{10} of the side switch arm f^3 . When the arm f^3 is on this contact the circuit would be continued through the back release relay J to the private wiper v^2 . Normally however this magnet is cut off.

The magnet J through its armature j controls the spring contacts j' and j^2 , which when the armature is attracted ground the wire 41 leading to the release magnet I, which is connected through wire 42 to the main battery wire 32. It will be observed that the armature of the private magnet P controls the springs p' , p^2 and p^3 the latter two of which also control a ground connection for the magnet I by way of wire 37 and spring d . It is necessary however that both magnets D and P be energized in order to close this circuit, and as P is controlled by F, this means that both vertical and rotary relays D and E must be energized. 125 130

Although a controlling means is not shown in the drawing the magnet P controls the side-switch F. When the restoring magnet I permits the parts to return to 5 normal, the switch arms of switch F are all returned to the position shown in Fig. 1. At each retraction of the armature of magnet P these switch arms are all advanced one step by means of an escapement 10 controlled by the said armature. This will be referred to again in the statement of operation.

Before leaving Fig. 1 reference should be made to the magnets L and N, and also to 15 the arrangement of multiples shown. The magnets L and N are register magnets, and the multiples shown are arranged for party line signaling. In considering both of these let us glance first at the general layout hereinbefore stated. It will be remembered that each line has a first selector such as shown in Fig. 1. This first selector not only has the individual selective wipers v' , corresponding to the answering jack, but it 20 also has multiple contacts m' , etc. (Fig. 2) with which these selecting contacts cooperate. These multiples m' represent the terminals of wires 13 and 14 leading to the various second selector switches. These 25 correspond to trunk lines in a manual exchange, and as they are only used at any one time by a limited number of subscribers, they are much fewer in number than the first selectors, say amounting to ten per cent 30 thereof. The same may be said of the connectors, which are further extended trunks. Now the multiples m' in the first selectors 35 represent second selectors, and the multiples in the second selectors represent the 40 connectors. The multiples in the connectors however directly represent and are connected to the subscribers' lines and their first selectors. In the drawings Fig. 3 shows a connector. The multiple contacts 45 m^5 on the connector for the line 19-20 appear in Fig. 4. The same connector would contain a pair of multiple contacts as say m^9 (Fig. 1) corresponding to the line 1-2, provided the said line 1-2 fell in the same 50 hundreds division, to which that connector is appropriated. Observe the multiple contacts $m^9-m^{11}-m^{13}$ and m^{15} (Fig. 1) belonging to the line 1-2 are distributed so as to be located in different connectors. The 55 connectors are arranged in groups, and since we use the decimal system in the present case for convenience, each group has the multiple terminals of subscribers whose numbers all have the same hundreds digit. 60 Thus there will be one group of connectors for subscribers from 1 to 100, another group for those from 101 to 200, another from those from 201 to 300, and so on. In the same way the second selectors are divided 65 into groups according to the thousands, and

each second selector has multiple terminals for all the connectors within its thousand. Thus there will be multiples in one group of second selectors for all the connectors between 1 and 100, that is 100, 200, 300, 70 and so on to 900, which within itself selects up to 999. To select a given line the first selector is operated to select the thousands or the hundreds group required, and finally the connector is operated to 75 select the line. By preference we put the ringing generator connections in the connector circuit, and since the connectors are in groups we can give each of several groups different varieties of current for 80 ringing, or differently connect the generators, as from one side of the line to ground or from the other side to ground.

Referring now to Fig. 1 which shows a party line having four telephones, instead 85 of simply multiplying the line to its normal set of terminals as m^9 in the first hundred bank connectors (assuming its number we will say to be 12), it is multiplied to the number 12 terminals in the first hundred 90 bank of connectors, to the number 12 terminals in the second hundred bank of connectors, to the number 12 terminals in the third hundred bank of connectors, and to be number 12 terminals in the fourth hundred 95 bank of connectors. The bells at stations A, A', A² and A³ are all in ground taps from the rotary side of line, each with a condenser, and each adapted to respond to a different frequency of ringing current, 100 A to 20 cycle current, A' to 40 cycles, A² to 60 cycles and A³ to 80 cycles, for ringing. Four generators are provided at the central office, giving respectively 20, 40, 60 and 80 cycle current. Every first hundred 105 group of connectors derives its ringing current from the 20 cycle generator, every second hundred group of connectors derives its ringing current from the 40 cycle generator, every third hundred group 110 from the 60 cycle generator, and every fourth hundred group from the 80 cycle generator. It will be understood therefore that the multiple contacts m^9, m^{11}, m^{13} , and m^{15} accompanied by their private or busy 115 contacts m^{10}, m^{12}, m^{14} and m^{16} , are distributed in the four groups of connectors referred to, and any station on this line 12 can be selectively rung by selecting the proper hundreds group of connectors and 120 then getting number 12. This means that in the present case subscriber A would be called as number 12, subscriber A' as number 112, subscriber A² as number 212 and subscriber A³ as number 312. The calling 125 subscriber exercises no judgment in the matter, but simply takes the number as he finds it in the directory, and works his transmitter or calling dial accordingly.

It should be noted that by this arrangement 130

ment the number of individual or first selector switches is not increased at all. Neither is there any increase in mechanism in any of the switches, the only change being that each 5 party line appears in as many groups of connectors as there are subscribers on the line, and each subscriber has his own independent number.

Means are thereby provided whereby any 10 subscriber on the line can call any other, and in fact it is quite possible for a subscriber to ring his own bell by selecting back his own station, even with the receiver off the hook.

15 Referring now to the call registers, attention is first directed to the fact that we have here double connections for each line, those to the first selector switch corresponding to the answering jack, and those to the multiple 20 tips in the connectors, corresponding to the multiple jacks in a manual multiple board. We state this analogy because we consider our invention need not be limited to an automatic system, being equally applicable to a manual system. We shall not 25 describe such a system at length because we do not consider it necessary, for any person skilled in the art will be able to apply the invention from the following description.

30 There are two classes of calls we wish to register, in-coming and out-going, that is those which originate at other stations but for any reason are "reversed", and those originating at the home station, respectively. Hence we provide two registers, and since out-going calls use the first selector or answering jack switch, we put the corresponding register in the circuit of that switch, by 35 means of a branch 421 of the rotary wire 12. It is true that the magnet L is thus included directly in the talking circuit, but its impedance may be neutralized by a copper jacket, or it may be shunted by a non-inductive resistance r' , which will pass voice currents without much interference.

40 In-coming calls come over the multiples, hence we put the in-coming or neutral relay N in a branch 43 in series with the connections to the multiple contacts, from the rotary wire 12, the other connection from wire 11 being made by branch 44.

Having thus described the apparatus and 45 circuits of Fig. 1 in general, we will pass to the second selector, Fig. 2, connector, Fig. 3, and the trunk line Fig. 1^a. Fig. 2 shows the second selector. After this has been selected by the first selector, the controlling magnets and apparatus of the latter are cut 50 out, the switch-arms of switch F pass onto their third contacts, f^{20} (Fig. 1), and the metallic circuit 11-12 is continued through to the conductors 13-14 by way of the contacts $v'-m'$ as indicated in heavy lines. 55 The operation of the impulse transmitter

at the substation is repeated to affect the vertical and rotary relays D² and E² of the second selector. The side switch F' of this selector normally stands with its arms f^4 , f^5 , f^6 , and f^7 on their first contacts f^0 . The 70 wire 13 is connected through a branch 45 with the magnet D² and thence to the main battery wire 32. The rotary wire 14 is connected by branch 46 to the magnet E² and thence to the battery wire 32. The armature of magnet D² controls a spring d' and a mechanically connected but electrically insulated spring d^2 which latter closes on the ground contact g' when the armature is attracted. The armature of magnet E² controls a spring e' and a mechanically connected but electrically insulated spring e^2 which latter closes on the ground contact g' when the armature is attracted. The two springs d' and e' have curved ends adapted 80 to come together when both armatures are simultaneously attracted at the point marked x , but not when either armature is attracted alone. When these close together they complete the circuit for releasing the two 85 selectors by magnets J and I' through the path: battery B, wire 32, 50, I', 51, 48, e' , x , d' , 47, 49, m^2 , v^2 , 52, J, 53, f^3 , f^{20} , and ground back to battery. Operated by itself the magnet D² controls the circuit of the vertical 90 magnet D³, which also passes through the contacts of the private relay P², the latter controlling the escapement of the side switch F', as in the first selector. When the single impulse comes over the rotary side of line 100 as before, this private magnet moves the side switch a step to cut in the rotary magnet E³, and the latter acts automatically to rotate the switch, as in the first selector, until cut out by the final movement of the side 105 switch to its third contacts and the completion of the talking circuit past the switch.

Referring to Fig. 3, we will describe the connector apparatus, and then will outline the operation of our entire system. In the 110 first place it will be observed that the wires 15 and 16 which constitute the talking circuit through the connector are not electrically continuous, as they are in the first and second selectors, but are separated in the 115 middle by condensers C, C'.

As a matter of convenience, we have designated the two ends of this connector circuit as 15-16 and 15'-16', respectively. Connected from the wire 15 by branch 55, is the 120 vertical relay D⁴, joined on the other side by wire 56 to the spring 57 of a cut-off relay R². This spring is normally in contact with springs 58 and 59, the latter connected to battery wire 32 and the former connected by 125 wire 61 with the spring 62 of the ringing relay W, this spring being normally in contact with spring 63 from which wire 60 leads to the rotary relay E⁴, and thence to the rotary side of the line. The relays D⁴ and E⁴ 130

are thus bridged across the wires 15—16. R' is a cut-on relay, the function of which will presently appear.

The vertical relay D⁴, through its armature, controls spring d³, and the mechanically connected but electrically separated spring d⁴, the latter cooperating with the ground contact g². The rotary relay E⁴, through its armature, controls a spring e³ 10 and an electrically insulated but mechanically connected spring e⁴ also adapted to close upon the ground contact.

It will be remembered from the previous statements that the connector not only steps 15 up its wipers v⁵ to the desired row of contacts m⁵ (Fig. 4), but also steps around the wipers to the desired line contact. Hence we have the vertical magnet D⁵, which does the vertical stepping, controlled by the relay 20 D⁴, its circuit passing from the spring d⁴ by way of the wire 64, through the normally closed springs p², p' of the private magnet P³, by wire 65 to the arm f⁴⁰ of the side switch F², thence by wire 66 to the magnet 25 D⁵, and by wire 67 to the main battery wire 32. The first succession of impulses over the vertical wire 15 operates the magnet D⁵ through the relay D⁴. This places the wipers vertically. The single impulse over 30 the rotary wire then closes the private magnet circuit, steps the side switch F² around one contact with all its arms f⁴⁰, f⁵⁰, f⁶⁰, f⁷⁰. This substitutes for the vertical magnet D⁵, the rotary magnet E⁵. The final selective impulses over the vertical wire 15 then operate the relay D⁴ and the magnet 35 E⁵ to bring the wipers v⁵ on the contacts m⁵ of the line 19—20 wanted. This series of impulses is followed by a single impulse as 40 before, over the rotary side of line, which again actuates the private magnet and this moves the side switch F² into its third position so that its four arms rest upon their last contacts f²⁰. The arms f⁵⁰ and f⁶⁰, it will be 45 observed, have completed the talking circuit (marked in heavy lines), and the rotary and vertical magnets are entirely cut out. The ringing relay W, however, is cut in by way of wire 69 and contact f²⁰ through wire 65 50 back to the contacts of relay D⁴. When the calling subscriber presses his ringing button, and thereby grounds the vertical side of line once more, this energizes the relay D⁴, completing a circuit from ground through 55 springs g² and d⁴, wire 64, springs p² and p', wire 65, side-switch arm f⁴⁰, side-switch contact f²⁰, wire 69, and relay W to battery. This energizes the ringing relay W, which breaks the through talking circuit and connects the ringing generator wire 170 through the spring 71' to the rotary wire 16' on the called side of the break, and so to the wire 18, the ringer Q' and ground.

The two magnets R² and R' are bridged

across the line, with the main battery interposed. They both receive current when the called subscriber answers, this current flowing over the metallic circuit 15'—17, 19,—station A⁴—20—18—16', and back to battery. The cut-on relay R' is adapted to complete a 70 bridge across the calling end of the line, including the battery B and the relays X and Y, by the following path: battery B, wire 71, relay Y, wire 72, spring 73, spring 74, wire 75, wire 16, back to the calling subscriber's station through the wires 14 and 75 12, out again through the wires 11 and 13 to the wire 15, and by wire 76 to spring 77, spring 78, wire 79, relay X, and ground back to the battery. When the magnet V³ is energized, this bridge circuit is completed and the talking battery is put on the calling subscriber's line. At the same time, however, we cut off the magnets D⁴ and E⁴ for the reason that if they were left in bridge when 80 the battery is connected across the line, they would operate simultaneously, and by making contact at the point x would close the release circuits of the releasing magnet J² and of the back release relay J', whereupon 90 the entire connection would be broken down. To prevent this, we put in the cut-off relay R². The relays R² and R' are constructed so as to have the same electrical characteristics. However, relay R' is equipped with a set of 95 springs which make contact when the relay is energized, whereas the springs of relay R² serve to break contact when it is energized. Consequently if these relays are simultaneously energized the springs controlled by 100 the armatures of the relays will affect their operation in such a manner that the springs of relay R² will break before the springs of relay R' will make. Conversely, when the relays are simultaneously deenergized, their respective spring combinations will affect the relay operation so that the springs of relay R' will break before the springs of relay R² will make. Therefore, the springs 57, 58 and 105 59 of relay R² are separated, and the connections of the relays D⁴ and E⁴ are broken before the relays X and Y and the main battery are bridged across the wires 15—16. In practice it might be difficult to obtain relays of like electrical characteristics. However, notwithstanding this fact, and assuming that the relay R' might close its contacts before the relay R² opens its contacts, the time interval during which the contacts of relays R' and R² are both closed will be 110 120 of such short duration that a relay or electromagnet included in such circuit will not receive sufficient current for its operation. Obviously if such a condition should arise, it could be readily overcome by making relay 125 R' slightly slow to pull up and to release.

When these relays X and Y are connected, X to the wire 15 and Y to the wire 16, they

serve thereafter to control the release circuit, as will be pointed out in the statement of operation.

The relays X and Y, like the relays R² and R', are designed with like electrical characteristics and control respectively a break and a make contact. These two relays function exactly the same as relays R² and R', and obviously relay Y could also be made slightly slow to pull up and release. Therefore, when these relays are simultaneously energized, the contact of X will open before the contact of Y closes, and conversely when the relays are deenergized, the contact of Y will open before the contact of X closes. The release circuit controlled by these relays requires the simultaneous closing of the contacts of relays X and Y. If the calling subscriber hangs up his receiver before the called party does, the subscriber's loop will be opened at the calling party's station, and this will open the circuit containing the relays X and Y which will therefore be deenergized. However, as the subscriber momentarily grounds both sides of the line directly after the subscriber's loop is opened, the relay Y, which is connected from battery to the rotary side of the line, will be momentarily energized and again close its contact. Therefore, as relay X is deenergized and relay Y momentarily energized, the release circuit 70 will be momentarily closed and release the switches. This circuit will be described in detail hereinafter.

We will now refer to Fig. 1^a, and will describe the repeating trunk circuit therein shown. The underlying principle of this circuit is that in trunking calls the proper place for the trunk line insertion is before the point of selection of the highest number in any exchange. As will appear from the statement of operation, the first selectors pick out idle trunk lines leading to the second selectors, simultaneously selecting the thousands number. In an exchange above ten thousand there would be another set of selectors ahead of the second selectors, of course, but the trunk is always inserted after the first selector. At this point difficulties are experienced in practice in transmitting the impulses over the trunk line with rapidity and certainty, and this difficulty is heightened, by the necessity for the insertion of condensers in the trunks. When then repeaters are used for repeating impulses around the condensers, the condenser discharge blurs the repeated impulses to a very marked degree. We have found a means to obviate this, and at the same time to provide for certain other requirements in connection with the registering and the control of pay stations. In putting a call through, where it is to be registered at the calling end, as already noted, we have provided a polarized

register magnet L (see Fig. 1), which does 65 not respond to the ordinary signaling current to register, but when reversed current is thrown back on the line it does respond to indicate that a call has been completed. In order to secure this operation upon the completion of the connection, it will be understood that all that is required is to make the connections from the main battery to the cut-on side of the connector circuit (see Fig. 3) such that current will flow in the proper 70 direction to register when cut back. Here we wish to call attention to the fact that while we have shown but one battery, we are not limited to one battery, and in fact, in practice, especially where reversals of current are required, as in trunking, or in differential registering, several batteries may be employed.

The trunk circuit shown in Fig. 1^a will now be described with special reference to 85 the automatic system herein shown, but it will be understood that its use is not limited to this specific system and that it is applicable to any system of signaling in which repeating is required.

In Fig. 1^a, which is supposed to be interpolated between Fig. 1 and Fig. 2, we have shown the multiple contacts m' in the banks of the first selectors, connected by the trunk wires 13-14' and 14-13' to a second selector, located at the distant office. Each side of the trunk is conductively divided but inductively made continuous by the condensers C². The wire 13-14' continues as the vertical side of line, while the wire 100 14-13' continues the rotary side. Impulses coming over the vertical side of the second selector cannot pass the condenser C² directly, but must be repeated, and the same with the other side of line. We therefore 105 provide the repeater Z, having its relay z connected to the wire 14 by the wire 90, and by wire 91 through cut-off contacts 92, 93 and 94 to the battery B³. Similarly the relay z' is connected by wire 95 to wire 13 and 110 thence by wire 96 and through contacts 93 and 94 to the battery B³. The contacts 92, 93 and 94 are normally closed, but adapted to be opened by magnet Z⁵, which is in a branch circuit 97-98 extending from the battery 115 B³ to two relays Z' and Z² by branches 99 and 100, and thence to the respective contacts 101 and 102 of the oppositely polarized relays Z³ and Z⁴. These relays are in series 120 in the circuit 103, which terminates in the two contacts 104 and 105 lying on opposite sides of the ground contact 108. The armature z² of the relay z controls the long spring 106, and the armature z³ of the relay z' controls the long spring 107, and these two armatures also control the springs 104 and 105. When either relay is energized, it grounds 125 its spring 104 or 105, and when both are

energized together they close the contacts 106 and 107 together.

The relays Z' and Z^2 respectively control the armatures 109 and 110, which in turn control the continuity of the branch circuits 111 and 112 with the back supply circuit 113, 114. Each of these branches has a battery connection, and these battery connections are relatively reversed, as shown by 10 the batteries B' and B^2 . Adapted to be bridged across the circuit 113-114 with one or the other of the batteries B' or B^2 , are the two relays Z^6 and Z^7 , the first controlling a front contact 115 and the second a back 15 contact 116. When both relays are attracted, one contact is open, and the armatures are connected in series at 117. These armatures and these contacts jointly control the continuity of the branch 118 of the trunk 20 release circuit 119 leading from the battery B^3 to the back release contacts m^2 . A parallel branch 120 is controlled by the two springs 106-107.

Impulses over the vertical wire 13 affect 25 the relay z' , which repeats into the wire 13' by grounding its contact 105, and thereby grounding the said wire 13' through the branch 123. Similarly, impulses over the rotary wire 14 affect the relay z , which repeats into the wire 14' by grounding its contact 104 and thereby completing the branch 121. Ordinarily the repetition would be straight from wire 13 into wire 14', and 30 from 14 into 13', but when such is the case the impulses repeated are blurred or somewhat smoothed out, particularly when transmitted at high speed, by the discharge of the condenser. We avoid this by transposing 35 the wires at 125 so that the condenser discharge in each case is into the opposite wire from that into which the repetition goes. The repetition and battery currents therefore go straight through, while the talking 40 circuit is transposed, but obviously the latter makes no difference. We have shown several transpositions, but these are not always necessary, and in fact, when we speak of a transposition at 125, the term is merely 45 relative, as we mean by this only the connection of the wires 121 and 123 for repeating, to opposite sides from those inductively connected through the condensers to the sides in which the respective impulses originate.

50 The operation of our system, apparatus and methods will have been largely understood from the preceding description; but we will here briefly review the same.

Taking the system shown in Figs. 1, 2, 55 3 and 4, we will first assume a call originating over the line 1-2 from the station A (number 12) and intended for station A^4 in Fig. 4. Subscriber A first takes down his receiver, R, and turns his impulse transmitter (not shown) so that after the rising of

the hook a ground circuit will be completed from G through the resistance r and contacts a^2-a to the vertical side of line 11, current flowing out over this path from the battery B through wire 32, contacts k', k^2, k^3 , 70 wire 31, relay D and line wire 11. The first number of impulses sent we will say is one, assuming the number of station A^4 to be 1920. Relay D controls magnet D' to step up the spindle v until the wipers v' register with contacts m' in the first row of second selector contacts in the bank. As the impulse transmitter at station A comes to rest, it momentarily closes together the contacts $a'-a^2$, which sends one impulse out from 80 battery B through wire 32, springs $k'-k^2$, wire 33 and relay E over wire 34, side switch wiper f^2 to wire 12, to the substation and to ground. Relay E attracts its armature and closes spring e on the ground contact g , thus 85 completing circuit through the private magnet P, which lets the side switch F step around one contact. In doing so, the arm f passes onto contact f^{10} and so cuts in the magnet E' , which immediately takes current 90 through the wire 39, and battery wire 32, vibrating continuously until cut out. This vibration is produced by the armature separating contacts when attracted, this being represented in the diagram throughout by a 95 pair of points normally touching each other between the magnet coils and adapted to be separated by an insulating point on the armature. The armature also rotates the spindle v so that the wiper v^2 passes from one 100 pair of multiple contacts to another, touching one before it leaves the last one, and continuing around until it reaches an idle pair, which means an idle second selector, which again means a selector without any ground 105 on the wire 49. By making the wiper v^2 bridge the contacts without a break between them it passes over those that are busy because the busy ones being grounded through the wire 49, to hold up the escape 110 magnet P by current over the following path: battery B, 32, P, 390, 40, $f^{10}, f^3, 53$; J, 52, $v^2, m^2, 49$, and ground. The instant an idle selector contact is reached this grounded circuit is broken, and the magnet 115 P lets go its armature, with the result that the side switch F is released to position 3, the rotary magnet E' is cut off and the arm f is open, the arms f' and f^2 each pass on to its third contact f^{20} , completing the talking 120 circuit and disconnecting the controlling relays and magnets therefrom, while the arm f^3 passes on to its third contact and closes the ground by wire 54 to the wire 53 through magnet J and wire 52 to the wiper v^2 , contact m^2 and wire 49, this being utilized later on in restoring the apparatus, as will be noted hereafter.

We now have the station A connected through to the second selector circuit (Fig. 130

2). The calling subscriber again turns his transmitter dial to send nine impulses, by closing the contacts $a-a^2$ together nine times and afterwards the contacts $a'-a^2$ together once as before. The nine impulses cause the vertical relay D^2 to be energized nine times over a circuit from battery, wire 32, through the relay D^2 , wire 45 and wire 13, back through wire 11 to the substation. The relay D^2 attracts its armature nine times to ground the spring d^2 thereby closing the circuit of the vertical magnet D^3 nine times, which steps up the spindle v of the second selector nine rows to the row of the nine hundreds in the connector contacts m^3 . The single impulse that follows over the rotary wires 12 and 14 passes through the relay E^2 , which grounds the spring e^2 and thereby closes circuit from battery, wire 32, through the private magnet P^2 , the latter permitting the side switch F' to move all its arms f^4, f^5, f^6 and f^7 around one step, the arm f^4 cutting in the rotary magnet E^3 , and the arm f^7 connecting the wiper v^4 back through the magnet J' and P^2 to the battery wire 32. The rotary magnet, being in circuit, commences to vibrate and step around the spindle v as before, until the wipers v^3 and wiper v^4 find contacts of connectors that are idle, or, in other words, ungrounded. In this connection we should call attention to the fact that the instant the spindle v in Fig. 1 (first selector) commenced to rise, it released a spring u (see the left-hand side of the figure) of a switch U , breaking circuit with contact u' of the bridging cut-off relay K , and grounding the wire 35 on the contact u^2 . This completed a circuit from ground as follows: G, $u^2, u, 35, o', o, 36$, and to all the contacts m^{10}, m^{12}, m^{14} , and m^{16} in the multiple banks of connectors upon which connection might be made with the line 1-2. These private bank contacts all being grounded, will test busy, therefore, if anyone else attempts to break in by calling line 1-2. Similarly, the instant connection was made between the first selector and the second selector at v^2, m^2 , the side switch arm f^3 moved into its third position, connecting ground on the wire 54 and so through the wire 53, magnet J , and wire 52 to the wiper v^2 , and thence to all the connected multiple contacts m^2 of the second selector shown, wherever they might be distributed, so that no first selector could get in on that second selector while thus in use.

As soon as the second selector finds a connector that is idle, the ground circuit through magnet P^2 (Fig. 2) is broken, the side switch F' makes its last step, the arms f^5 and f^6 complete the metallic circuit 13-14 onto 15-16, the arm f^4 cuts off the rotary magnet E^3 , and the arm f^7 connects the ground of contact f^{20} to the magnet J' , and so to the wiper v^4 , which, being on the con-

tact m^4 , makes it and its connected multiple contacts of the connector thus selected test busy thereafter during the connection.

The circuit has now been traced to the connector shown in Figure 3, with a clear metallic circuit made up of wires 11, 13, 15, on one side, and 12, 14, 16 on the other side. This is the connector, which actually selects the contact of the line wanted. We find the side switch F^2 present in this case also, and that it controls the circuits of three magnets, the vertical magnet D^5 , the rotary magnet E^5 , and the ringing relay W .

The subscriber now sends the number 2, which causes two impulses to pass along the wires 15, 13 and 11 and to ground at station A, through the connector circuit as follows: battery, wire 32 to spring 59, to springs 58 and 57, wire 56, relay D^4 and wire 55 to wire 15. This vertical relay D^4 is thus energized and it in turn closes a circuit containing magnet D^5 which then steps up the spindle v until its wipers v^5 and v^6 reach their respective second rows of subscribers' contacts. The single impulse over the rotary side 16 of the line from the battery B by wire 32, springs 59-58, wire 61, springs 62-63, wire 60, to relay E^4 , wire 16, and back to the subscriber's station operates relay E^4 which grounds the spring e^4 , closing the circuit of the private magnet P^3 . In moving its armature, the magnet P^3 lets the side switch go around one contact, cutting in the rotary magnet E^5 , and connecting the wiper v^6 through the arm f^{10} and contact f^{10} , to the spring p^3 to prepare a circuit to release the connector if the desired line is found to be busy.

The subscriber now sends the number 0, which is ten impulses over the vertical side 105 of the line. This again operates the vertical relay D^4 as before, which grounds the spring d^4 and this time closes the circuit 64, $p^2, p', 65, f^{20}, f^{10}, 68, E^5, 67, 32$. This brings the wipers v^5 and v^6 onto the individual contacts m^5 and m^6 in the multiple bank of the connector S^2 in Fig. 4. The grounding of the rotary side of the line at the substation will operate relay E^4 . The operation of relay E^4 will close the circuit 115 containing magnet P^3 and the operation of the latter will close a contact at springs p^3 and p^4 . Now, if the called line is busy, the contact m^6 will be connected to ground, as a result either of the operation of switch 120 U (Fig. 4) or, due to the ground circuit, to wiper v^6 by way of side switch arm f^{10} of the switch used in the set-up connection. Therefore, when the magnet P^3 is operated and the wiper v^6 is connected to the terminal of the busy line, a circuit will be completed from ground by way of wiper v^6 , arm f^{10} , springs p^3 and p^4 , relay J^2 , and wire 32 to battery. This will operate the relay J^2 which, in attracting its armature, 130

releases the stop pawls which retain the spindle v in its rotated and elevated position, and thus the switch is restored to normal.

- 5 The operation of the magnet P^3 does not affect the side switch F^2 , and as the connector switch is released as soon as the magnet P^3 is operated when the called line is busy, the side switch F^2 is likewise released 10 and cannot pass out of its normal position when the magnet P^3 is deenergized.

The calling subscriber will next operate his ringing button. This will close a circuit containing the vertical relay D^4 over a path 15 to ground, from the subscriber's station (Fig. 1), through resistance r , contacts a^4 , a^3 , a^{13} , a^{14} , a^6 , and a^5 to wire 26, and thence by wires 3, 11, 13 and 15 to the vertical relay D^4 , wire 56, springs 57, 58 and 59, wire 20 32 to battery. The operation of the vertical relay D^4 will close the circuit of the vertical magnet D^5 , which in turn will raise the spindle v one step. As soon as the switch takes its first vertical step from normal, springs 101' and 102' of the off-normal switch close and thereby complete a circuit from ground to the secondary busy-back transformer H , springs 101' and 102' and side switch arm f^{60} to the rotary side 30 of the line, and thence out to the substation and back of the vertical side of the line and through relay D^4 , to battery. This gives the calling subscriber a busy tone. The calling subscriber will then hang up 35 his receiver and will therefore momentarily ground both sides of the line which will simultaneously operate relays D^4 and E^4 . These close their contact springs d^3 — e^3 at point x , whereby the following circuit is 40 completed: battery B , wire 32, magnet J^2 , e^3 , d^3 , wire 700 to contacts m^4 , wiper v^4 , relay J' arm f^7 , contact f^{20} and ground. The relay J' and magnet J^2 both act, the latter to restore the connector S^2 and the former to close the circuit B , 32, 50, magnet I' , 51, 49, m^2 , v^2 , 52, relay J , 53, arm f^3 , contact f^{20} , 54, and ground, whereupon the magnet I' pulls out the pawls that hold the spindle v of the second selector S' (Fig. 2), 45 and restores this to normal. The relay J closes the circuit of the release magnet I as follows: battery B , 32, 42, I , 41, j^2 , j' , and to ground, whereupon magnet I pulls out the jawls from the spindle v of the first 50 selector (Fig. 1) S , and permits it to go to normal. The magnet I , magnet I' and magnet J^2 in each case, when releasing the pawls from the switch spindles also pulls over the side switches F , F' or F^2 to the normal or 55 zero position shown in the figures. When the spindle v of the first selector S drops down, it takes the ground off the wire 35 by pushing down the spring u of the switch U . Thus all parts are again normal and all 60 switches idle.

Suppose, however, that the line wanted does not test busy. The subscriber, after sending in his last number presses his ringing button which closes a contact at the springs a^{13} and a^{14} to ground the vertical 70 side of line as follows: G , r , springs a^4 — a^3 , a^{13} , a^{14} , a^6 , a^5 and by wire 26 to the vertical side of line. This permits current to pass back from battery, wire 32 in Figure 3, through vertical relay D^4 to the subscriber's 75 station and ground. The spring d^4 is again grounded, and a circuit is completed from ground, through springs p^2 — p' and wire 65 to arm f^{40} , contact f^{20} , wire 69, the ringing relay W and battery. This relay attracts its 80 armature opening the vertical side of line 15' entirely. It also opens the rotary side of line 16' and connects the forward end thereof through its terminal 71' to the ringing generator wire 170. Current then passes 85 out through wire 16', lower wiper v^5 , lower contact m^5 , wire 18, wire 20, ringer Q' and to ground through the condenser at the wanted station A^4 .

After ringing, the calling subscriber A releases his calling button, the vertical relay and the ringing relay in Figure 3 deenergize and the metallic talking circuit is clear through from one station to the other, as marked in heavy lines, except for the interposed condensers C' . All magnets and relays are disconnected, and all grounds are cut off, except that the relays D^4 and E^4 are connected from the vertical and rotary side of the line, respectively, to the springs of 95 the cut-off relay R^2 , and these springs in turn are connected to the battery B ; whereas the relays R^2 and R' are connected in series with the battery B , this circuit being bridged across the wires 15'—16' leading to 100 the called subscriber's station A^4 . The latter bridged connection is adapted to give current to the subscriber A^4 in Figure 4 over his metallic circuit; but it should be particularly noted that there is no bridged talking battery on the metallic circuit back to the calling subscriber. 110

The called subscriber A^4 we will suppose now answers by taking down his receiver. His switchhook thereupon rises and closes 115 his metallic talking circuit, whereupon current flows from the bridged battery through the two relays R^2 — R' out to the station A^4 and back. Both relays attract their armatures, but the springs of relay R^2 break contact before the springs of relay R' make contact, and thereby cut off the vertical and rotary relays D^4 and E^4 , before the relays X and Y are cut on, with their bridged battery connections. If it were not for this cut-off 120 there would be a short-circuit through the relays D^4 — E^4 , which were bridged, and they would work the release mechanism by closing their contacts d^3 — e^3 at the point x .

When the relay R' acts, it cuts on the re- 130

lays X and Y and bridges the main battery across the connector wires 15—16, so that talking current now flows back through the metallic circuit to the calling station A.

5 Subscriber A thus gets current for his telephone transmitter T.

Both relays X and Y now hold up their armatures during the connection, and it is to be observed that this keeps the release cir-

10 cuits of the back release relays open, because the contacts $x'-x^2$ of the relay X are open, although the others $y-y'$ are closed. The relays D⁴ and E⁴ being cut-out, their release contacts are open at x .

15 At the conclusion of the conversation, when subscriber A hangs up, he breaks the metallic circuit and momentarily grounds both sides thereof by closing together the springs a^{10}, a^{11}, a^{12} . The opening of the sub-

20 scriber's loop deenergizes the relays X and Y, and the subsequent momentary grounding of both sides of the line momentarily energizes relay Y, as previously explained. This closes a circuit from the ground on side

25 switch contact f^{20} (Fig. 2), by way of side switch arm f^1 and relay J' to wiper contact v^4 and contact m^4 , and thence by way of wire 700, contacts x^2 and x' , wire 70, contact y and y' to release magnet J², and by way

30 of wires 750 and 32 to battery. The release magnet J² will thus be energized, and in drawing up its armature pulls out the retaining pawl of the spindle v of the connector, Fig. 4, restoring this switch to normal. The relay J', Fig. 2, closes the local circuit of the release magnet I' of the second selector through wire 49, and the back release relay J of the first selector, which in turn closes the local release circuit of re-

40 lease magnet I of the first selector. The operation of the release magnets associated with the various switches will restore all of these switches to normal.

If the subscriber A⁴ hangs up his receiver first, the relays R² and R' will be de-energized. The relay R' will be momentarily reenergized, however, when both sides of the lines are momentarily grounded. This will close the release circuit through

50 relay J' and magnet J² hereinbefore described, and the various switches will be restored to normal in a manner similar to that described when the subscriber A is the first to hang up his receiver.

55 We have thus described the operation of our common battery system for a complete call, cutting back the talking battery to the calling subscriber when the called subscriber answers. It remains to describe the opera-

60 tion of our trunking apparatus.

Referring again to Figure 1^a the trunk line we show is adapted to form an extension from a given first selector in one office to a group of second selectors in a different office, as stated. In Figure 2 will be found a line

marked "line of trunk connection". The ends of the two wires 13' and 14' in Figure 1^a are supposed to be connected directly to the wires 13—14, where they are cut by this line, the wire 49 in Figure 2 being the same 70 as wire 49' in Figure 1^a. Considering the trunk line to be interpolated between the first and second selectors, therefore, and having the trunk broken by the condensers C², the operation is as follows: 75

The transmission of impulses and selection of an idle trunk through its contacts m^1 — m^2 , is the same as before, the first selector then connecting the subscriber's line through on to an idle interoffice two-wire trunk. The 80 second set of impulses coming over the vertical wire 13 cannot pass on into the second selector circuit direct because of the condenser C². The circuit now is from the battery B³ (Fig. 1^a), through the springs 94, 85 93, and by wire 96 to relay z', wire 95 to wire 13, and so back to the subscriber's station and ground over the vertical wire. The relay z' when energized grounds the contact 105 by forcing it against the contact 108, and thereby grounds the wire 13' by the following path: 13', 124, 123, 105, 108, to ground. For each impulse, current will then flow back from the battery B, Figure 2, through the vertical relay D², through wire 45, arm 95 f^3 , contact f^0 , wire 13, wire 13'. (Figure 1^a), and so to ground as stated. The operation of the mechanism in the second selector circuit is the same as already described.

The single impulse that comes over the 100 rotary side 14 travels through the circuit B³, 94, 93, 92, 91, relay z, 90, 14, and over the rotary wire back to the calling subscriber's station to ground. The relay z grounds the contact 104 at 108, grounding the wire 14' 105 through wire 121. The subsequent impulses are transmitted to the selectors and connector in the same manner. This brings us to the next step, which is the cutting back of battery of the proper polarity when the 110 called subscriber answers. It will be remembered that the direction of current flow which goes back to the calling subscriber's station is determined by the direction in which the battery B is connected across the circuit 15—16 by the cut-on relay R' in Figure 3. Flow of current from this battery cannot go all the way back to the calling subscriber's station, however, because of the condensers, not to mention the drop 115 that would result from the resistance of a long trunk if there were no condensers. We will suppose the connection to have been completed, and the called subscriber to have answered. His answering energizes the re-

lays R', R². Relay R² cuts on the battery B across wires 15—16 to send current back from the free pole of the battery through the wire 16 and from the latter through 14', 121, 104, contact 130, bridge wire 103, 130

through the two polarized relays Z^4 and Z^3 in series, back to contact 131, spring 105, wire 123, and wire 13' to the wire 15 and back to the grounded side of the battery.

- 5 The direction in which the battery B is connected across the circuit in Figure 3 determines which of the relays Z^3 — Z^4 will attract its armature, for these are oppositely polarized. Supposing it to be Z^3 , this closes 10 the local circuit 101, 99, relay Z' , 98, relay Z^5 , 97, battery B^3 , and ground. Relay Z^5 opens the circuits of the repeater relays z and z' at the springs 92—93—94. At the same time the relay Z' closes the circuit 15 ground, battery B' , 111, 109, 113, relay z^6 , wire 14, 12, back to the calling subscriber's station, out again, wire 11, 13, relay Z, wire 114, to ground at the upper armature of relay Z' . In other words, battery B' is 20 bridged across the wires 13—14 in the same direction as the original battery in the connector circuit, Figure 3. Suppose that current over trunk conductors 13', 14' to have been reversed, then the polarized relay Z^4 25 would have attracted its armature and in operating relay Z^2 would have connected the reversed battery B^2 to send back current. Thus, the direction of the current supplied to the calling subscriber is controlled 30 through the repeater. Due to the reversal of the current flow in the rotary side of the line caused by the operation of relay Z^2 as described, the central office service meter L, polarized to respond to this current flow, 35 would operate. If the trunk line is very long, several of these repeater circuits may be used to off-set the excessive trunk line resistance. The calling line, even if connected over a long distance line, therefore, would 40 receive current of the proper direction.

This brings us to the question of releasing, which is the last step to be considered. The relays z and z' on the calling end of the trunk when they both attract their armatures close the contacts 106 and 107 together, thereby closing the release circuit traced as follows: battery B^3 , wire 119, 107, 106, 119 and contact m^2 in the multiple bank m of the first selector, Figure 1, thence in 45 Figure 1 by wire 52 through relay J and to ground. Relay J operates the release magnet I to return the first selector to normal. The simultaneous attraction of the armature of relays z and z' will likewise simultaneously ground the two sides 13' and 14' 50 of the trunk circuit by means of their springs 104 and 105. This will cause the restoration to normal of all of the rest of the switches used in setting up the connection as described, except that the circuit for release magnet I' of the second selector leads 55 to ground by way of conductor 49' of the repeater. This is the release that would occur if the subscriber A hung up without 60 completing the connection. After the called 65

subscriber has answered, however, one of the batteries B' or B^2 is cut back and bridged across the calling end and at the same time the relay Z^5 opens the contact at springs 92—93—94 and cuts off the two relays z and z' . The bridge through these relays is opened to prevent their operation by the bridged battery and a consequent premature release of the switches, and to remove them from the talking circuit. 70 Some means must therefore be provided for breaking the connection and restoring the first selector in case subscriber A hangs up first. Of course, if the called subscriber hangs up first the relays z and z' would again be cut in and then, when the calling subscriber hung up, they would act as we have stated to clear out. 75

The relays Z^6 and Z^7 serve to control the release of the first selector switch from the 80 calling subscriber's end when the called subscriber has his receiver off the hook. When the calling subscriber hangs up his receiver before the called subscriber does, he opens at the subscriber's station the circuit containing the relays Z^6 and Z^7 , which will therefore be deenergized. However, the subsequent momentary grounding of both sides of the line will reenergize relay Z^6 . 85 This closes the release circuit from ground (Fig. 1), wire 54, side switch contact f^{20} , side switch arm f^3 and relay J to wiper v^2 and contact m^2 (Fig. 1^a), wire 119, contact 90 115, and armature of relay Z^6 , armature and contact of relay Z^7 , wires 118 and 119 to battery B^3 . Thus relay J will be energized. 95 The actuation of relay J will cause the operation of release magnet I which will restore the first selector switch. 100

While the invention is shown as applied 105 to a call charging arrangement it is to be understood that it is not so limited but may be used for example in semi-automatic working for operating the calling supervisory relay to control a lamp to indicate 110 the response of the called party at the distant office.

What is claimed is:

1. In a telephone system, incoming lines, offices wherein said lines terminate, trunks 115 consisting of two conductors only interconnecting said offices, automatic switching means, means for building up connections by means of said switching means and trunks, an electro-responsive device associated with each trunk at the originating office, means operated at a certain stage in establishing an inter-office connection to supply current to the trunk to cause the operation of said device, and an electro-responsive element controlled by said device. 120

2. In a telephone system, subscribers' lines, offices wherein said lines terminate, trunks consisting of two conductors only interconnecting said offices, automatic 125

- switches, means for building up connections by means of said switches and trunk lines, an electro-magnetic responsive device connected to each trunk at the originating office, means operated upon the completion of an inter-office connection to supply current to the trunk to cause the operation of said device, and an electro-responsive device controlled by said device.
10. 3. In a telephone system, subscribers' lines, offices wherein said lines terminate, trunks consisting of two conductors only interconnecting said offices, automatic switching means for interconnecting said lines, electromagnetic call charging means for said lines, and means automatically operated by the completion of an interoffice connection to supply current to the inter-office trunk to cause the operation of said 20 charging means.
4. In a telephone system, the combination with subscribers' lines, offices wherein said lines terminate, trunks consisting of two conductors only interconnecting said offices, automatic switching means for interconnecting said lines, electromagnetic call charging mechanism associated with said lines, means to supply current for operating said switching means that will not operate 30 said mechanism and means to subsequently supply current to said two conductor trunk to cause the operation of said mechanism.
5. In a telephone system, the combination with subscribers' lines, offices wherein said lines terminate, trunks consisting of two conductors only interconnecting said offices, automatic switching means for interconnecting said lines, electromagnetic call charging mechanism associated with said lines, 35 means to supply current for operating said switching means which flows in a direction that will not operate said mechanism, and means controlled in finally completing an interoffice connection to change the current 40 flow in the said two conductor trunk to cause the operation of said mechanism.
6. In a telephone system, the combination with subscribers' lines, offices wherein said lines terminate, trunks consisting of two conductors only interconnecting said offices, automatic switching means, electromagnetic call charging mechanism associated with said lines, means to supply to said trunk and switches in the establishment of a connection 50 current flowing in a direction which will not operate said mechanism, and means controlled in finally completing an inter-office connection to reverse the current flow in the trunk line to cause the operation of 55 said mechanism.
7. In a telephone system, subscribers' lines, a meter for each line, offices wherein said lines terminate, trunks consisting of two conductors only interconnecting said offices, a meter control relay connected to each 60
- trunk, automatic switching apparatus for interconnecting said lines, a source of current supply, and means under the control of the called subscriber to an interoffice connection for supplying current to the said two conductor trunk to operate said meter control 70 relay to cause the same to operate the calling line meter.
8. In a telephone system, the combination with subscribers' lines, offices wherein said lines terminate, trunks consisting of two conductors only interconnecting the same, automatic switching means, a meter individual to each line, a meter control relay connected to each trunk, and means operated by the response of the called subscriber on an interoffice connection to apply current to said interoffice trunk to operate said 80 relay, and a circuit thereby closed to operate the calling line register.
9. In a telephone system, the combination with subscribers' lines, a meter for each line, offices wherein said lines terminate, trunks consisting of two conductors only for interconnecting said offices, automatic switching means to establish a connection between a calling and a called subscriber's line, a polarized relay connected to said inter-office trunk, means controlled in the final completion of a connection to supply current over said trunk to operate said polarized 90 relay and means controlled by said polarized relay for operating said meter.
10. In a telephone system, the combination with subscribers' lines, offices wherein said lines terminate, trunks consisting of two conductors only interconnecting said offices, automatic switching means for interconnecting said lines, a polarized register serially included in one limb of each subscriber's line, a polarized relay connected to each trunk line, means to supply current for the operation of said switching means which flows in a direction that will not operate 95 said register, and means for supplying current to said trunk line upon the completion of an inter-office connection which flows in the proper direction to operate said polarized trunk relay, and means controlled by the operation of said trunk relay for supplying current to the calling line in the proper direction to operate its register.
11. In a telephone system, the combination with subscribers' lines, offices wherein said lines terminate, two conductor trunks 100 interconnecting said offices, a polarized meter serially connected in each subscriber's line, a polarized relay for each inter-office trunk line, means to supply current for the operation of said switching means which flows in a direction that will not operate 110 said meter, means for applying current to said trunk line when the connection is completed which flows in the proper direction to operate its polarized relay, and means 115
- 120
- 125
- 130

controlled by said relay for reversing the current flow to the calling line for operating its meter.

12. In a telephone system, subscribers' lines, each line provided with a meter, means including a two-conductor trunk line for establishing a talking circuit between a calling and a called line, a relay bridged across the trunk for controlling the meter of a connected calling line, and a second relay connected in bridge of the connected called line for controlling said first relay.

13. In a telephone system, subscribers' lines each line provided with a meter, means including a two-conductor trunk line for establishing a talking circuit between a calling and a called line, a relay connected to the talking conductors and individual to each trunk line for controlling the meter associated with a connected calling line, and a second relay connected in bridge of the connected called line for controlling said first relay.

14. In a telephone system, subscribers' lines, offices wherein said lines terminate, two-conductor trunks interconnecting said offices, automatic switches, means for building up a connection by means of said switches and trunk lines, a polarized electro-magnetic device connected to said trunk line at the originating office, means operated upon the completion of a connection for applying current to the interoffice trunk line which flows in the proper direction to operate said device, and an electro-responsive device controlled by said polarized electro-magnetic device.

15. In a telephone system, subscribers' lines, offices wherein said lines terminate, two-conductor trunks interconnecting said offices, automatic switches, means for building up a connection by means of said switches and trunk lines, a polarized relay for each trunk at the originating office, means operated upon the response of the called party for applying current of the proper direction to the inter-office trunk line to operate said polarized relay, and an electro-responsive device controlled by said polarized relay.

16. In a telephone system, subscribers' lines each provided with a call register, means including a trunk line for establishing a talking circuit between a calling line and a called line, a relay for said trunk line for controlling the register associated with a connected calling line, and a second relay for the called line for controlling said first relay.

17. In a telephone system, subscribers' lines each provided with a meter, means including a trunk line for establishing a talking circuit between a calling line and a called line, a relay individual to said trunk line for controlling the meter associated with a con-

nected calling line, and a second relay in bridge of the connected called line for controlling said first relay.

18. In a machine switching telephone exchange system, subscribers' lines each provided with a meter, means including automatic switches and a trunk line for establishing a talking circuit between a calling and a called line, a relay for said trunk line for controlling the meter associated with a connected calling line, and a second relay for the called line for controlling said first relay.

19. In a machine switching telephone system, subscribers' lines each provided with a call register controlling magnet, means including automatic switches and a trunk line for establishing a talking circuit between a calling and a called line, a relay for said trunk line, means controlled in finally completing a connection to supply current over said trunk to operate said relay, and a circuit for operating the call register controlling magnet of the calling line closed by the operation of said relay.

20. In a machine switching telephone exchange system, subscribers' lines each provided with a call register controlling magnet, means including a dial at the calling substation, automatic switches controlled by said dial and a trunk line for establishing a talking circuit between a calling and a called line, a relay for said trunk line, means controlled in finally completing a connection to supply current over said trunk line to operate said relay, and a circuit for operating the call register controlling magnet of the calling line closed by the operation of said relay.

21. In a machine switching telephone exchange system, subscribers' lines each provided with a meter, means including automatic switches and a trunk line for establishing a talking circuit between a calling line and a called line, a polarized relay for said trunk line, means controlled in finally completing a connection to apply current to said trunk to operate said relay, and a circuit for operating the call register controlling magnet of the calling line closed by the operation of said relay.

22. In a machine switching telephone exchange system, subscribers' lines each provided with a meter, means including automatic switches and a trunk line for establishing a talking circuit between a calling line and a called line, a polarized relay for said trunk line, means controlled by the response of the called subscriber for applying current to said trunk to operate said relay, and a circuit for operating the call register controlling magnet of the calling line closed by the operation of said relay.

23. In a machine switching telephone exchange system, subscribers' lines each provided with call charging means, means in-

cluding automatic switches and a trunk line for establishing a talking circuit between a calling and a called line, a pair of polarized relays for said trunk line, means controlled in finally completing connections to certain of said subscribers' lines to supply current to said trunk line to operate one of said relays, a circuit for operating the call charging means of the calling line closed by the operation of said relay, a circuit for supplying talking current to the calling line closed by the operation of said relay, means controlled in finally completing connections to others of said subscribers' lines to supply current to said trunk line to operate the other 15 of said polarized relays, and a circuit for supplying talking current to the calling line closed by the operation of said latter relay.

In witness whereof, I hereunto subscribe my name this 20th day of December A. D., 20 1921.

JACOB W. LATTIG.

In witness whereof, I hereunto subscribe my name this 22nd day of December A. D., 1921.

CHARLES L. GOODRUM.
